CLAIM

The ornamental design of a front medial portion for a vacuum cleaner, as shown and described.

DESCRIPTION

FIG. 1 is a perspective view of a front medial portion for a vacuum cleaner showing our new design;

FIG. 2 is a top plan view thereof; and,

FIG. 3 is a front elevational view thereof.

The portion of the vacuum cleaner shown in broken lines is for illustrative purposes only and forms no part of the claimed design. The surfaces or portions of the article not shown in the drawing or described in the specification form no part of the claimed design.
